UNITED STATES PATENT OFFICE.

JAKOB ADRIAN, OF OBERURSEL, GERMANY.

STOPPING MECHANISM FOR SHOE-SEWING MACHINES.

Application filed October 27, 1924, Serial No. 746,164, and in Germany March 1, 1924.

It is well known in shoe sewing machines to stop the driving shaft in a position suitable for the removal and the introduction of the work. To this end the driving shaft has been braked and then stopped by a rigid stud or the like. It is also not new to control the stopping mechanism by balance weights in order to stop the shaft at a predetermined speed.

It is the object of the present invention to stop the driving shaft of a shoe or like sewing machine without shock in a predetermined position and at a predetermined speed. This object is attained by drawing the brake-band taut, by a stud secured to a balance weight revolving with the shaft. When the speed of the shaft diminishes to a predetermined degree the stud on the balance weight operates the brake. Preferably a spring connected to the foot-treadle clutching and declutching the machine operates to draw the brake-band to some degree preparatory to drawing it taut before the stud of the balance weight becomes operative.

In the accompanying drawings—

Figure 1 shows the parts of the stopping mechanism while the machine is running at normal speed;

Figure 2 is a cross-section of the line A—B of Figure 1;

Figure 3 illustrates the starting wedge α in the position corresponding to Figure 1;

Figure 4 shows the parts while the machine is stopped;

Figure 5 is a cross-section on the line B—C of Figure 4;

Figure 6 illustrates the starting wedge α in the position corresponding to Figure 4;

Figure 7 shows another embodiment of the invention in the position occupied while the machine is running;

Figure 8 is a vertical section of the parts shown in Figure 7;

Figure 9 corresponds to Figure 7 with the parts in the stopped position.

Referring to Figure 1 the driven shaft 1 journaled in the head of the machine receives its motion from the shaft 2. The shaft 2 is propelled by the loose pulley 3 when the friction discs r , s , are pressed against each other. This is done by the wedge g of the treadle m depressed against the action of the spring n .

On the shaft 1 there is keyed a brake drum z co-acting externally with the brake-band t . The brake-band is connected at one end

to the bolt w of the brake lever v and at the other end to the shackle z . The latter is adjustable on the shaft y . The brake lever v is pivoted to the bar t of the starting treadle m . By depressing the treadle the brake-band k is released; on the other hand the brake-band is drawn taut when the starting treadle is raised by the spring n .

The balance weights c , d , are pivoted on the bolts b within the drum a . They are connected to each other by the link e . The spring f fastened at one end to the drum and at the other end to the weight c tends to keep the weights in the inner position shown in Figure 4. When the shaft 1 is running with the normal speed the weights are carried by their centrifugal force into the outer position shown in Figure 1. By releasing the treadle m the shaft 2 is declutched and the parts t , v , draw the band k taut. The speed of the shaft diminishes rapidly until at a certain point the balance weights returning to their inner position act to stop the shaft 1.

To this end the brake-band k is connected by the shackle z to one end of a two-armed lever i pivoted on the shaft y . The other end of the lever i is adapted to come into contact with the stud g of the weight c when returning into the inner position. The lever i has a hooked part i'' pivoted on the bolt l . The spring i' is so arranged as to swing the hooked part i'' on the bolt l away from and out of engagement with the stud g . So long as the shaft 2 is coupled to the driving pulley 3 (see Figure 1) the stopping stud g does not operate. On the other hand when the treadle is freed, the wedge-shaped end x of the brake-lever v raises and swings the nose of the lever-part i'' into the path of the stud g . As soon as the stud g , moving with diminishing speed, comes under the nose of the lever part i'' and enters its notch h , it drags with it the lever i and draws the band k taut to such a degree as to stop the drum a with the shaft 1, see Figures 4 and 5. By adjusting the shackle z a relatively fast or slow stopping may be obtained.

By depressing the treadle m the band k is released, the wedge x lowered and the lever part i'' frees the stud g .

From the foregoing it will be apparent that the new mechanism obviates a sudden stopping of the revolving parts, which upsets the accurate adjustment of the different

sewing instrumentalities. If however the brake-band is drawn taut at a predetermined low speed of the machine the shocks may be diminished to a harmless degree.

5 To stop the machine the treadle *m* is released. The spring *n* acts through the levers *m*, *t*, and *v* to draw the brake band *k*. The speed of the shaft 1 diminishes and the weight *g* swings inward until its stud *g* engages the hooked end *i''* of the lever *i* and definitely stops the machine.

In the embodiment shown in Figures 7 to 9, the separate journals for the levers *i*, *v*, are dispensed with. Moreover the lever *i* swings on the hub *o* of the journal of the shaft to be stopped itself. This lever carries, as in the example already described, by means of the shackle *z*, one end of the band *k*, while the other end of the band is attached to the bolt *w* of a slide *p*. This slide is arranged at the upper end of the bar *t* and is guided by its gudgeon *u* in the vertical slot of the lever *i*. The gudgeon *u* projects with its flattened end from the slot 25 and is adapted to come into contact with the stud *g* of the weight *c*. With the weights, swung out the gudgeon is inoperative, see Figure 7. But as soon as the treadle is released the speed diminishes and the spring *f* brings the weights into their inner position; the stud *g* comes into contact with the gudgeon *u* and tends to drag it along. By this means the lever *i* is swung out and the brake-band is drawn taut.

35 What I claim is:—

1. In a stopping mechanism of a shoe sewing machine, a driven shaft, a brake drum on the driven shaft, a brake band on the drum, and a balance weight revolving with the shaft and adapted to draw the band taut, a spring counter-acting the centrifugal force of the balance weight, a spring drawing the brake band preparatory to drawing it by the balance weight, and

a treadle unclutching the machine operated 45 by the said spring.

2. In a stopping mechanism of a shoe sewing machine, a driven shaft, a brake drum on the driven shaft, a brake band on the drum, a balance weight revolving 50 with the shaft and adapted to draw taut the brake band, a member carrying one end of the brake band and adapted to come in the path of the balance weight, and means connected to the treadle for bringing the 55 said member into the said path.

3. In a stopping mechanism of a shoe sewing machine, a driven shaft, a brake drum on the driven shaft, a brake band on the drum, a balance weight revolving with 60 the shaft and adapted to draw the band taut, a member carrying one end of the brake band and adapted to come in the path of the balance weight and to act as a stop for the rotating shaft when the band is drawn 65 taut, a treadle for unclutching the machine, and means connected to the treadle for bringing the said member into the said path.

4. In a stopping mechanism of a shoe 70 sewing machine, a driven shaft, a brake drum on the driven shaft, a brake band on the drum, a balance weight revolving with the shaft and adapted to draw the band taut, a lever revoluble about the shaft and 75 carrying one end of the brake band, a member carrying the other end of the brake band and adapted to come in the path of the balance weight, a treadle for unclutching the machine, and means operated by the 80 treadle for moving the said lever and the said member relatively to each other in order to draw the brake band taut about the brake drum.

In testimony whereof I affix my signature.

JAKOB ADRIAN.
